UNITED STATES PATENT OFFICE.

THOMAS THOMSON, OF SCUNTHORPE, ENGLAND.

MACHINERY OR APPARATUS FOR HANDLING, MANIPULATING, OR TRANSPORTING STEEL AND LIKE METAL PLATES.

1,305,319.

Specification of Letters Patent.

Patented June 3, 1919.

Application filed March 1, 1919. Serial No. 280,107.

To all whom it may concern:

Be it known that I, THOMAS THOMSON, a subject of the King of Great Britain and Ireland, and resident of Scunthorpe, in the 5 county of Lincoln, England, have invented new and useful Improvements in Machinery or Apparatus for Handling, Manipulating, or Transporting Steel and like Metal Plates, of which the following is a specification.

10 This invention has relation to the handling, manipulation or transportation of steel and like metal plates (hereinafter referred to as plates or as metal plates), in relation to machinery or apparatus, such, 15 for example, as shearing machines, punching machines, bending machines, or in or about workshops or yards, and the invention has for its object to provide machinery or apparatus by means of which certain advantages shall be obtained.

The handling, manipulation or transportation of metal plates in relation to machinery or apparatus in or by which they are acted upon or treated, or in or about work- 25 shops or yards, is usually effected by manual labor, though proposals to use machinery or apparatus for the work have been made. In connection with machinery or apparatus for the purpose mentioned it has also been 30 proposed to employ electromagnets.

The present invention provides machinery or apparatus for the handling, manipulation or transportation of metal plates in relation to other machinery or apparatus or in or about workshops or yards and machinery or apparatus in accordance with this invention comprises, *inter alia*, an electromagnet or electromagnets.

Machinery or apparatus for the purpose 40 as specified and in accordance with this invention comprises a carriage or a pair of independent carriages mounted to run upon a track or on tracks either on or above the ground, a jib or extension of rigid construction mounted on the carriage or on each of the carriages, an electromagnet or electromagnets mounted on each of the jibs or extensions, means for moving the carriage or carriages on the track or tracks and means 45 for moving the electromagnet or electromagnets on each of the jibs or extensions above the face of the plate to be handled, manipulated or transported independently of the movements imparted to the carriage 50 or carriages.

Further, in accordance with this invention, machinery or apparatus as described is used in combination with friction reducing means comprising a bed or plurality of rollers or casters or both, said friction reducing means 60 being arranged either at ground level or at a convenient height thereabove.

When the carriages are mounted to run on a track laid upon the ground, they are capable of movement only in two directions, 65 but when the track upon which they run is mounted on what may be called a secondary carriage which is itself mounted to run on a track at right angles to that of the track it carries, the two carriages are capable of 70 simple or compound movement.

The jibs or extensions of rigid construction are mounted upon the carriages and extend therefrom either forward, sidewise, or downward, and their mounting may be 75 such that they are capable of movement independent of that of the carriage.

Each electromagnet or the electromagnets is or are mounted upon its jib or extension or their jibs or extensions so as to be mov- 80 able in relation thereto.

Referring to the accompanying drawings:

Figure 1 is a diagrammatic sketch plan;

Fig. 2 is an elevation and Fig. 3 is a plan 85 view of a carriage with jib or side extension;

Fig. 4 is a plan and Fig. 5 is an elevation of another construction of carriage; and

Figs. 6 and 7 are similar views to Figs. 4 and 5 of a further modification.

1 is the usual cross cut shears and 2 is the side shears. Interposed between the cross cut and side shears 1, 2 are friction 95 reducing means comprising a plurality of rollers 3 and casters 4. The casters 4 are preferably of non-magnetic material and are mounted upon swiveling supports 6 so that the plates 5 can be moved both longitudinally and laterally. 7 is a track arranged at the side of the rollers and casters and in front of the shearing machine on which two carriages 8, preferably electrically propelled, are adapted to run. The carriages 8 105 have jibs or extensions 9 of rigid construction which are mounted on the carriages 8 at adjacent ends thereof and project over the rollers 3 and casters 4. The carriages may thus be regarded as right and left 110

handed. Each jib or extension carries an electromagnet 10. The disposition of the carriages 8 relative to each other and to the plate 5 is such as to permit the electromagnets to exert their influence on the plate at any point intermediate its ends. The electromagnets 10 are carried by cross heads 11 which slide in guides 12 in the jibs or extensions 9, and gearing 13, such as worm 10 and wheel and a screw, preferably driven by an electric motor 14, is provided upon each carriage to actuate the electromagnet and move it longitudinally of its jib or extension and laterally of the carriage. The electromagnets are nearly counterbalanced by weights 15 and their positions relatively to the plate adjusted by handles 17 which act on ropes 16 passing over and under pulleys 18 on the jibs or extensions and electromagnets. Other convenient means for this purpose could be employed.

In the several examples illustrated, each magnet 10 is carried by and provided with a central upwardly extending post or spindle 20 fixed thereto. The operative connection between the magnet and its cross head or carriage 11, and its controlling cables 16, is established through the medium of said spindle. The spindle maintains the lateral position of the magnet with respect to the cross head and jib, although I do not wish to limit all features of my invention to the employment of such spindle.

The operation of the apparatus described is as follows:

The plate 5 to be sheared passes through the cross cut shears 1 over the rollers 3 and on to the casters 4. The carriages 8 have been, or are, moved along the track 7 and when the jibs or extensions 9 are above the plate, the handles 17 are actuated and the magnets dropped into contact with the plate and energized. If rolling supports, such as either or both rollers 3 and casters 4 are not provided, the handles 17 are then again actuated and the magnets with the plate are moved upward, and the weight of the plate taken wholly by the electromagnets. When rollers and (or) casters are provided, as in the arrangement being described, the weight of the plate may be taken more or less or wholly off the casters 4. The carriages 8 are now traversed along the track 7 until the plate is brought opposite the shears 2. The gearing 13 associated with the electromagnets and it may be the carriages 8, is or are then operated to cause the plate 5 to be adjusted laterally until the line of shear is under the blade of the machine. In the arrangement illustrated and now being described, there are two carriages 8 and as each carries an electromagnet each end of the plate 5 can be adjusted independently and accurately. It will be understood that, in

some cases, it will be unnecessary to use two carriages 8, the electromagnet on the one carriage being sufficiently powerful to operate the plate. After one cut of the shears, the carriages 8 are traversed along the track 7 and the plate 5 is adjusted for another cut and so on. After one side or edge of the plate has been sheared, it is turned around and the carriages are moved in the reverse direction along the track so as to bring the other side or edge under the shear blade. Each of the carriages may be controlled by an operator traveling with it, or by a suitably located electrical control. The carriages may be driven hydraulically or otherwise, instead of electrically, and the electromagnets may be moved along the jibs or extensions in like manner. In the case of large outputs of plates to be sheared where one side shears could not accomplish the work, the casters 4 may be extended and a similar arrangement to that described above be fitted to cut the second edge.

In Figs. 4 and 5 the jibs or extensions 9 extend laterally from both sides of the machine and by this arrangement a greater degree of adjustment is provided than with the arrangement shown in Figs. 1 to 3 inclusive.

In Figs. 6 and 7 the jib or extension 9 is capable of a sluing motion about the carriage.

Having now particularly described and ascertained the nature of my said invention and in what manner the same is to be performed, I declare that what I claim is:

1. In apparatus for manipulating plates, in combination, machinery for operating on such plates, a supporting bed for such plates adjacent to such machinery, embodying a plurality of plate-engaging-rolling elements arranged to permit free movement of each plate thereon in any direction substantially parallel with the plane of the plate, a movable carriage provided with a magnet supporting jib projecting therefrom, a plate-shifting electro-magnet carried by said jib and adapted to be brought into plate shifting relation to the top surface of the plate on said bed for positioning the plate with respect to said machinery and shifting the plate to and from the same, and means for moving the electro-magnet independently of the movements of said carriage.

2. In combination, in apparatus for manipulating plates, machinery for operating on such plates, a supporting bed on which such plates can be shifted to and from and positioned with respect to such machinery, said bed embodying non-magnetic rolling elements provided with caster mountings to permit free movement of each plate on said bed in any substantially horizontal direction, and manually controlled means for

shifting each plate on said bed with respect to said machinery, said means embodying a movable carriage provided with a projecting jib, an electro-magnet carried by said jib and adapted to be brought into operative relation with the top surface of each plate, and means for shifting the position of the magnet with respect to the carriage.

3. In combination, machinery for operating on plates, a supporting bed on which each plate is shiftable in any substantially horizontal direction to and from and to position with respect to said machinery, and manually controlled mechanism for thus shifting each plate, said mechanism embodying a movable plate shifting carriage provided with a projecting jib, and an electro-magnet carried by said jib and adapted to be brought into operative plate shifting relation to the top face of each plate on said bed.

4. In combination, machinery for operating on plates, a manually-controlled movable carriage, a way for said carriage adjacent to the path traveled by plates to and from said machinery, a supporting bed for the plates along said path, an electro-magnet carried by said carriage and arranged over said bed, and manually-controlled means for shifting said magnet independently of the carriage, transversely of said bed and toward and from said machinery for accurately positioning the plate laterally with respect to said machinery.

35 5. In combination, mechanism for operating on plates, a plate supporting bed leading thereto and arranged in front thereof, a track approximately parallel with said bed, a carriage movable on said track and provided with means for propelling the same, said carriage provided with a jib overhanging said bed, an electro-magnet carried by said jib, and manually-controlled means for shifting said magnet horizontally 40 toward and from said mechanism, and maintaining the lateral position thereof with respect to said jib for accurately positioning

the plate laterally with respect to said mechanism.

6. In combination, machinery for operating on plates, a track, and manually-controlled mechanism for propelling plates, longitudinally to said machinery and for shifting them transversely toward and from and accurately positioning the plates laterally with respect to said machinery, said mechanism comprising a pair of separate carriages on said track, said carriages being movable independently and simultaneously on said track in either direction, each carriage provided with an electro-magnet arranged to engage the top face of the plate to be manipulated, each magnet having supporting means constructed and arranged to maintain the relative lateral position of the magnet during plate shifting and to enable the magnet to maintain its fixed position with respect to the plate while tightly gripping the same during horizontal swinging or shifting movements of the plate, and manually-controlled means for independently moving said magnets vertically and horizontally while engaging different portions of the same plate to coöperate in shifting and horizontally swinging said plate 65 either end foremost to accurately position the same transversely with respect to said machinery.

7. Means for manipulating plates, embodying a pair of manually-controlled independently-movable carriages, a way along which both carriages are movable separately in either direction and simultaneously in either direction, each carriage provided with and carrying an electro-magnet adapted to 80 overhang the plate to be manipulated, and manually-controlled means for independently moving said magnets with respect to their said carriages and with respect to each other to coöperate in laterally turning or 85 twisting and positioning an elongated plate, substantially as described.

Dated this 7th day of February, 1919.
THOMAS THOMSON.
